United States Patent Office.

WILLIAM PRICE, OF CINCINNATI, OHIO.

Letters Patent No. 96,481, dated November 2, 1869.

IMPROVED DUMPING-CAR FOR GRADING.

The Schedule referred to in these Letters Patent and making part of the same.

To all whom it may concern:

Be it known that I, WILLIAM PRICE, of Cincinnati, in the county of Hamilton, and State of Ohio, have invented certain new and useful Improvements in Dumping-Cars for Grading; and the following is a full, clear, and exact description of the same, reference being had to the accompanying drawings, making a part of this specification, in which—

Figure 1 represents an end view of the car-truck and body, the elevated supporting-frames and cam-trunnions or dumping-device on the track, in position for loading and carrying earth, &c.

Figure 2 shows an end view of the same, with the car-body tipped up on one side, in position for dumping or discharging its contents.

Figure 3 shows the inside of the plate of the cam-trunnions, with the flange and ribs for securing it firmly to the end of the car-body.

Figure 4 shows an edge view of the same, as secured to a broken-off section of the end of the body.

Figure 5 is a section through the same, showing the bolts and nuts for fastening it on.

Figure 6 shows a side elevation of the dumping-car, flanged trunnions, supporting-frames, truck-wheels, and track complete.

The object of my invention is to furnish increased facilities for removing earth, in grading roads, streets, or for street or other railroad-tracks, or for excavating for canal, mill-races, or other purposes; and

It consists—

First, in a single car-body or earth-receiver, so constructed that no gates or side openings are required in it, to discharge the load or contents on either side of the truck, at the pleasure of the operator.

Second, in the arrangement for hanging and balancing the car-body on cam-journals or irregular-shaped trunnions, secured on the outside of the ends.

Thirdly, in the construction of the trunnions or dumping-device, and their supporting-frames, so that the car-body will resume its position centrally on the truck, for loading and transporting, and will admit of being tipped up and over, on either side, sufficiently to discharge the contents by a man or boy.

To enable others to make and use my improvements in dumping-cars, I will describe them more fully, referring to the drawings, and the letters marked thereon.

The truck-frame A may be made of hard-wood joist or plank, and secured together by bolt-rods *a a*, extending through both the side pieces, they being so placed, in relation to the cross or end-pieces of the truck-frame, as to support the elevated frames B B, on which the body C hangs.

The car-body or earth-receiver C may be made of hard wood; the frame-timbers *b b* may be light, and of small dimensions; and the box or lining *c* may be of thin plank or boards, and be sufficiently strong and durable for the purpose, as it can all be secured at the corners, and all of the joints in the firmest manner, there being no slides or doors to be opened, to discharge the contents, which, when used in the ordinary method of constructing dirt or coal-cars, very much weaken the body, and strain the joints, and wear out the slides.

The dumping-device or cam-trunnions D D are made of metal, with a projecting flange, *d*, and are provided with ribs *e e*, to fit on to the cleats *f f* on the ends of the car-body C, and are secured by bolts nearly central, the under portion being so shaped that it finds the centre of the supporting-frames B B, and rests securely on a level when the car is empty, but when filled full, the larger portion of the contents being above the line of its bearings, it is very easily lifted from either side by taking hold of one of the handles *g*, secured to the bottom for that purpose.

The side-pieces of the truck-frame A are also provided with stirrups *h h*, to put one foot in, so as to enable a boy or a man of low stature to easily lift the side of the car until it preponderates and dumps its load.

The supporting-frames B B are so shaped on the top, as to conform to the cam-trunnions D D, and form a stop on both sides, to prevent the body from being cast off in dumping.

The advantages of my improved dumping-car are that they can be made much lighter in proportion to their capacity for carrying a load, and are more durable, there being no doors or hinges or slides to get disarranged or broken, and are operated, in discharging a load, in less time, and with greater ease, than any that have ever before come to my notice.

What I claim as my invention, is—

1. A single car-body, dumping on either side of the truck which supports it, as herein described.

2. Placing the supporting and dumping-device on the outside ends of the car-body, as and for the purpose herein-specified.

3. The cam-trunnions D D as constructed, in combination with the supporting-frames B B, car-body C, and truck A, all arranged to operate substantially as herein set forth.

In testimony whereof, I hereunto subscribe my name, in the presence of—

WILLIAM PRICE.
